J. E. Clokey,
Shutter Worker.
Patented Mar. 30. 1858.

No 19,751.

UNITED STATES PATENT OFFICE.

JNO. E. CLOKEY, OF WASHINGTON, DISTRICT OF COLUMBIA.

OPENING AND CLOSING OUTSIDE BLINDS.

Specification of Letters Patent No. 19,751, dated March 30, 1858.

To all whom it may concern:

Be it known that I, JOHN E. CLOKEY, of the city of Washington, in the District of Columbia, have invented certain new and useful Improvements in Apparatus for Opening and Closing Outside Blinds or Shutters; and I hereby declare that the following is a full, clear, and exact description of the same, reference being had to the accompanying drawings, making a part of this specification, in which—

Figure 1 represents a vertical transverse section in the plane 1—2 and Fig. 2 a horizontal section in the plane 3—4.

15 The letters of reference indicate the same parts in both figures.

The outside blinds *a*, and *a'*, are hinged to the window frame *b*, in the usual manner, at *c*. Bent levers *d* have their fulcra 20 at *e*, where they are secured to the frame by the pivot screws *f*, which pass loosely through holes in the levers allowing a slight degree of play. Guide bars *g*, are secured to the inside of the blinds, and move freely 25 in slots in the outer ends of the levers *d*, and are connected thereto by the vertical friction rollers *h*, which traverse between the bars *g*, and the plates *i*. Catches *k*, are fixed upon the frame to receive the 30 levers when the blinds are opened to their full extent, and to retain them in that position, and catches *l*, act in the same manner to secure the blinds when closed.

Gains *m*, are cut in the bottom of the lower 35 sash to admit of the free movement of the levers.

The blind *a*, being open and secured in that position by the lever *d*, which has fallen by its gravity into the notch of the 40 catch *k*, it is closed in the following manner. The stud or handle *o*, upon the inner arm of the lever is first pressed down, the angle *p*, of the lever becoming its fulcrum. The play upon the pivot screw allows the outer 45 end of the lever to be slightly elevated to the position shown in red lines in Fig. 1. This releases the lever from the catch *k*. The handle *o*, is then moved horizontally

toward the side of the frame, closing the blind by the action of the outer end of the 50 lever upon the bar *g*. By then removing the pressure from the handle, the gravity of the lever causes it to take into the catch *l*, thus securing the blind without further trouble, in such a manner that it cannot be 55 readily opened from the outside.

The blind is opened and thrown back against the outer wall, by pressing the handle down (this relieves the lever from the catch *l*) and then moving the handle 60 horizontally from the side of the frame toward its center; by again removing the downward pressure, the lever falls into the catch *k*, and the blind is again secured in its open position, as before described. 65

The blind can be secured in any partially open position by the addition of any simple contrivance, such as a pin passing through a hole in the inner lever arm, into one of a series of holes in an arc upon the window 70 sill, or in any other convenient manner, but this is not shown in the accompanying drawing.

My apparatus is simple and inexpensive, and may be readily applied to the common 75 form of outside blinds and shutters now in use.

I am aware that blinds and shutters have been opened and closed from the inside, by various complicated contrivances, but this 80 I do not claim broadly.

What I claim as my invention and desire to secure by Letters Patent of the United States is—

The combination of the bent levers *d*, 85 with the bars *g*, when they are constructed, arranged and operated in the manner herein described, and used and for the purpose specified.

In testimony whereof I have signed my 90 name to this specification before two subscribing witnesses.

JOHN E. CLOKEY.
